DESIGN FOR AN EARRING

Nathan Heyman, New York, N. Y., assignor to
Oscar Heyman & Brothers, Inc., New York,
N. Y., a corporation of New York

Application July 12, 1941, Serial No. 102,112

Term of patent 14 years

To all whom it may concern:

Be it known that I, Nathan Heyman, a citizen of the United States, residing at New York city, in the county of New York and State of New York, have invented a new, original, and ornamental Design for an Earring, of which the following is a specification, reference being had to the accompanying drawing, forming a part thereof.

Figure 1 is a perspective view of an earring

embodying my new design, the same being an earring designed to be worn on the left ear; and Figures 2, 3 and 4 are, respectively, a side elevation, a front view and a rear elevation of an earring embodying my new design.

I claim:

The ornamental design for an earring, as shown and described.

NATHAN HEYMAN.
